W. A. LUCAS.

RAIL TIE.

APPLICATION FILED DEC. 22, 1917.

1,259,756.

Patented Mar. 19, 1918.

Inventor

WILLIAM A. LUCAS

By Watson E. Coleman

Attorney

UNITED STATES PATENT OFFICE.

WILLIAM A. LUCAS, OF MOOREWOOD, OKLAHOMA.

RAIL-TIE.

1,259,756.

Specification of Letters Patent. Patented Mar. 19, 1918.

Application filed December 22, 1917. Serial No. 208,361.

To all whom it may concern:

Be it known that I, WILLIAM A. LUCAS, a citizen of the United States, residing at Moorewood, in the county of Custer and State of Oklahoma, have invented certain new and useful Improvements in Rail-Ties, of which the following is a specification, reference being had to the accompanying drawings.

10 This invention relates to railroad ties and has for its primary object to provide a metallic rail tie having cushioning means for the rails whereby the weight of the locomotive will be yieldingly sustained and 15 due wear upon the ties or displacement thereof obviated.

It is another important object of my invention to provide a tie of the above character which is so constructed that lateral 20 spreading movement of the rails will be prevented.

The invention has for an additional object to provide a metal tie structure of such form that the tie may be securely anchored upon 25 the road bed and held in place by the crushed rock or other ballasting material.

It is a further general object of my invention, to provide a railroad tie having the above noted advantageous features, which is 30 exceedingly strong and durable in its construction, light in weight, effective and reliable in practical use and which can be manufactured at relatively small cost.

With the above and other objects in view 35 the invention consists in the improved construction, combination and arrangement of the several parts as will be hereinafter more fully described, subsequently claimed and illustrated in the accompanying drawing in 40 which similar reference characters designate corresponding parts throughout the several views and wherein:

Figure 1 is a side elevation of my improved railroad tie showing the manner of ballasting the tie upon the road bed;

45 Fig. 2 is a longitudinal sectional view;
Fig. 3 is a top plan view;
Fig. 4 is a bottom plan view; and
Fig. 5 is a section taken on the line 5—5

50 of Fig. 3.
Referring in detail to the drawing 5 designates the base of the tie, 6 the opposite side walls thereof, 7 the end walls and 8 the top wall. This tie is preferably constructed of 55 cast metal and the several parts thereof may be assembled and secured together by any

preferred means, and the top wall 8 thereof is inwardly and downwardly curved from points in spaced relation to the ends of the tie to the center thereof, as shown at 9, the 60 lowest point 10 of said top wall being spaced above the bottom wall of the tie.

Spaced webs or panges 11 are formed upon the bottom of the tie body at the center and integrally connect the side walls thereof. 65 These flanges extend upwardly and at a longitudinal inclination in relatively opposite directions and substantially in parallel relation to the curved portions of the wall 8.

12 designates a pair of spring plates which 70 are secured at one of their ends in any preferred manner to the top side of a rectangular metal block 13 which is seated upon the base wall of the tie body between the lower ends of the spaced webs 11. These spring 75 plates 12 are longitudinally curved and extend in opposite directions between the curved top wall section 8 and in close proximity thereto. Each of said springs at its end is bolted or otherwise fixed to a metal 80 plate 14 which is disposed upon the underside of the spring plate 12 and extends across substantially the entire width of the tie. To this plate 14 the upper end of a coil spring 15 is secured, the lower end of said 85 spring being fitted within an annular retaining flange 16 upon the base wall of the tie. R designates the rail, which is secured upon the end of the spring plate 12 by the clamping 90 bolts indicated at 17.

Upon the underside of the base wall 5 of the tie, flanges or ribs 18 are integrally formed and extend along the longitudinal edges of the tie. These flanges are connected at intervals by means of the spaced 95 transverse ribs 19.

As seen in Fig. 1 of the drawing, the ribs 18 and 19 are securely embedded in the road bed and prevent the longitudinal or lateral shifting movement of the tie body. The 100 ballasting material indicated at B covers the central portion of the top wall of the tie filling the depression formed by the curved wall sections 9. Thus it will be manifest that the tie body is securely anchored or 105 held against shifting movement upon the road bed.

The top wall of the tie at the points where the rails extend across the tie are cut away and the side walls 6 of the tie 110 body are also notched or recessed as at 20 to permit of the depression of the rails

against the action of the springs 12 and 15, such downward movement of the rails being limited by the engagement of the rail bases upon the lower edges of the notches 20.

5 From the foregoing description taken in connection with the accompanying drawing, the construction and several advantages of my improved rail road tie will be clearly and fully understood. When the locomotive passes over the tie, the weight thereof is yieldingly cushioned by means of the heavy coil spring 15 and the spring plates 12 so that wear upon the tie is reduced to a minimum, and displacement of the ballast 15 is obviated. Also it is to be noted that by mounting the rails upon the tie in the manner above described, the rails are held against relative lateral spreading movement, thus obviating the possible wreckage of the 20 train; the several parts of the improved tie are of a relatively simple form, and can be constructed at small cost and readily assembled. The tie as a whole is very durable and relatively light in weight.

25 While I have herein shown and described the preferred construction and arrangement of the several parts employed it is to be understood that the device is susceptible of considerable modifications therein, and I 30 therefore reserve the privilege of adopting all such legitimate changes as may be fairly embodied within the spirit and scope of the invention as claimed.

Having thus fully described my invention what I claim and desire to secure by Letters Patent is:

1. In combination, a hollow metal tie having its top and side walls cut away adjacent its ends to permit of a limited downward movement of the rails, and a pair of 40 spring plates centrally held within the hollow tie and extending longitudinally in relatively opposite directions, the rails being secured upon the respective spring plates.

Copies of this patent may be obtained for five cents each, by addressing the "Commissioner of Patents, Washington, D. C."

2. In combination, a hollow metal tie having 45 its top and side walls cut away adjacent its ends to permit of a limited downward movement of the rails, a pair of spring plates centrally held within the hollow tie and extending longitudinally in relatively opposite directions, the rails being secured upon the respective spring plates, and additional coil springs arranged within the ends of the hollow tie and secured to the respective spring plates beneath the rails. 55

3. In combination with a hollow metal tie recessed adjacent its opposite ends to permit of the limited vertical movement of the respective rails, a pair of spring plates and a rigid connection between the same at one 60 of their ends, means centrally located within the tie body to retain the connecting means therein against shifting movement, said spring plates extending longitudinally of the tie in relatively opposite directions, 65 metal plates secured to the free ends of the spring plates upon which the rails are adapted to be secured, and a coil spring arranged within each end of the tie between the base thereof and one of said metal plates. 70

4. A hollow metal tie having yieldable rail supporting means therein, the top wall of the tie being downwardly and inwardly curved to the center of the tie to provide a depression for the reception of the ballast- 75 ing material.

5. A railroad tie having its upper surface longitudinally curved inwardly and downwardly from the ends of the tie to its center to provide a depression for the 80 reception of the ballasting material.

In testimony whereof I hereunto affix my signature in the presence of two witnesses.

WILLIAM A. LUCAS.
